BURNER

Garnet W. McKee, Rockford, Ill.

Application February 6, 1931. Serial No. 513,948

12 Claims. (Cl. 158—109)

The present invention relates to improvements in burners, and has particular reference to burners adapted for use with means for producing and supplying an adjustable proportionate mixture of fuel and air, such for example as a jet inspirator.

Jet inspirators commonly comprise a mixing tube, a chamber communicating with the inlet end of the tube and adapted to be supplied with one of the fluid constituents of the fuel mixture, and a nozzle for discharging a jet of the other fluid constituent of the fuel mixture, as the driving fluid, into the tube to induce a proportionate flow of fluid from the chamber into the tube.

In my copending application, Serial No. 427,713, filed February 12, 1930, I have shown a jet inspirator of the low pressure type in which the fuel is the induced fluid. The present invention relates to a burner comprising a jet inspirator of the high pressure type in which the fuel is the inducing fluid and atmospheric air is the induced fluid. The fuel and air ratio in the mixture flowing through the mixing tube is subject to adjustment by adjusting the area of the air inlet to the chamber about the fuel nozzle. The volume of fuel mixture supplied to the burner may be adjusted through the agency of a control valve in the fuel supply line.

Various objects of the present invention reside in the provision of a novel gas burner of the high pressure type which has a wide range of adjustment, which is not likely to back-fire even though the fuel pressure is reduced to minimum, which may supply the primary fuel mixture without blowing the flame away from the burner tip, and which has a relatively small overall length.

Another important object is to provide a new and improved burner of the high pressure type which constitutes part of the proportional mixer, and which is adapted to be positioned closely to the furnace tuyère, so that the mixture of fuel and air is not mixed intimately or completely within the burner tube, and hence is not so likely to result in back-firing as would a more perfect mixture.

A further object resides in the provision of a burner of the high pressure type comprising means for supplying one or more small pilot streams of gas to the burner tip which gas is available to supplement the gas in the primary mixture to maintain a final mixture of the desired proportions, and which serves to keep the burner ignited at all times.

Further objects and advantages will become apparent as the description proceeds.

In the drawing, Figure 1 is a view, partially in section of a burner embodying the features of my invention.

Fig. 2 is a view of the discharge end of the burner tube taken along line 2—2 of Fig. 1.

Fig. 3 is a sectional view taken along line 3—3 of Fig. 1.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to the drawing, the burner in its preferred form comprises a burner tube 10 of suitable form. In the present instance, the tube 10 is elongated, and is formed with a straight passage of which the inlet end is smoothly rounded on a relatively large radius as indicated at 11, and of which the discharge end is smoothly rounded on a relatively small radius as indicated at 12.

The burner tube 10 constitutes also the mixing tube of a fuel and air mixer which may be of any suitable form. In the present instance, the mixer comprises a casing 13 secured to the inlet end of the tube 10. The casing 13 is formed internally with a hollow central fitting 14 in spaced relation to the tube 10, and connected to a fuel line 15 adapted to supply fuel, such as gas or oil, from a suitable source under the desired pressure. A control valve 16 is interposed in the line 15 for adjusting the amount of fuel supplied. Opening from the fitting 14 is a restricted orifice or nozzle 17 discharging axially into the tube 10.

The rear of the casing 13 opens about the fitting 14 to the atmosphere to define a primary air inlet 18. A shutter 19 adjustably mounted on the casing 13 across the inlet 18 serves as means for regulating the amount of primary air supplied. Preferably, the orifice 17 is of such a size that with the shutter 19 completely open, insufficient air for complete combustion will be supplied through the inlet 18. It will be evident that the jet of fuel issuing from the orifice 17 will entrain or inject air from the casing 13 in a definite proportion, and will cause a primary mixture of fuel and air to pass through the tube 10 at a high velocity.

To provide means for supplying supplemental fuel directly to the burner tip, the tube 10 is

formed adjacent its outer end with an outer peripheral flange 20 defining an annular shoulder 21, and is formed intermediate the shoulder and the tip with an elongated peripheral recess 22. 5 An outer sleeve 23 is fitted snugly over the tube 10 and against the shoulder 21, and preferably is welded to the latter, thus constituting the recess 22 a closed annular fuel chamber. Formed in the outer periphery of the burner tip in spaced relation are a plurality of longitudinal pilot ports 24 adapted to discharge fuel from the chamber 22 about the mixture issuing from the tube 10. The inner or discharge end of the sleeve 23 defines a flat annular face 25 about the ports 24. 10 Fuel is supplied from the line 15 to the chamber 22 through a branch line 26. The line 26 is located at the burner side of the valve 16 so that the supply of gas to the chamber 22 is varied in the same relation as that to the orifice 17. Interposed in the line 26 is a pressure reducing means 27 of suitable construction. 15 Where the burner is intended for use on a furnace and not as a torch, a sleeve 28 is mounted in concentric spaced relation about the discharge end of the tube 10, and more specifically is formed on its outer end with an inner peripheral end flange 29 seating against an annular shoulder 30 formed in the sleeve 23. The other end of the sleeve 28 is formed with an outer peripheral flange 31 adapted to be mounted on a furnace wall 32 concentrically about an opening 33 formed in the latter. The opening 33 in the furnace wall 32 is larger than the outside diameter of the tube 10, and preferably is slightly flared inwardly. Formed in the peripheral wall 20 of the sleeve 28 are a plurality of longitudinally spaced secondary air inlet ports 34. A cylindrical air shutter 35 mounted on the sleeve 28 is formed with air inlet ports 36 corresponding in size and spacing to the ports 34, and is rotatably adjustable against the flange 31 to bring the ports 34 and 36 into various degrees of registration so as to control the supply of secondary air to the burner tip. 25 In operation, the shutter 19 normally is left wide open. The valve 16 is opened to supply gas or oil to the orifice 17 and at a reduced pressure to the chamber 22. A primary fuel mixture, deficient in air, thus is caused to flow at a high 30 velocity through the burner tube 10. Fuel jets which when ignited constitute pilot flames also issue from the ports 24 about the primary stream. The secondary air required for complete combustion of the primary stream as well as of the pilot streams is drawn through the ports 34 and 36 about the burner tip into the furnace opening 33. The pilot flames act continuously to keep the primary stream ignited, which is essential since the latter by reason of its high velocity would 35 otherwise tend to become extinguished. By reason of the small curvature at 12 and the flat surrounding face 25, the primary fuel stream does not tend to blow out the pilot flames, but on the contrary, tends continuously to draw the pilot flames and the secondary air toward itself. Thus, the pilot flames act constantly to keep the burner 40 ignited.

It will be evident that the fuel-air ratio of the final mixture may be made exactly correct for complete combustion, or may be varied over a substantial range to obtain a reducing flame or an oxidizing flame as desired. Due to the partial primary mixing of fuel and air and the complete utilization of the velocity pressure, a fast moving 45 but slow burning mixture results. Hence, a flame

having very desirable characteristics is obtained, and the fuel pressure can be reduced considerably below the normal low point of operation of high pressure burner without the likelihood of back flashing.

I claim as my invention:

1. A burner comprising, in combination, a burner tuyère, a burner tube mounted in operative relation to said tuyère, means for supplying a proportionate gaseous fuel mixture under a high velocity to the inlet end of said tube, a fuel supply line connected to said means, a line branching from said first mentioned line for supplying a restricted quantity of supplemental fuel to the discharge tip of said tube about the periphery thereof, pressure reducing means in said last mentioned line, and adjustable means for supplying secondary air about said tip to said mixture and said supplemental fuel. 80
2. A burner comprising, in combination, a burner tuyère, a burner tube having a longitudinal passage opening therethrough, a sleeve fitting about said tube and defining an annular space therewith, a plurality of spaced ports opening from said space through the tip of said tube to 90 said tuyère, a casing open to the atmosphere and connected to the inlet end of said tube, a nozzle in said casing discharging axially into said tube, valve controlled means for supplying fuel to said nozzle, and means for supplying supplemental fuel at a reduced pressure from said first mentioned means to said space. 95
3. A gas burner comprising, in combination, an elongated burner tube having a discharge tip at one end, an atmospheric air casing opening 110 to the other end of said tube, a restricted injector nozzle mounted in said casing to discharge axially into said other end of said tube, a gas supply line connected to said nozzle, means for discharging a restricted quantity of supplemental 115 gas to said discharge tip about the periphery thereof, and a line branching from said first mentioned line for supplying gas to said means. 105
4. A burner comprising, in combination, a burner tube having a straight longitudinal passage opening therethrough, the inlet end of said passage being flared on a relatively large radius and the outlet end of said passage being flared convexly on a relatively small radius, a sleeve fitting about said tube and defining an annular 120 space therewith out of communication with said passage, the end of said sleeve defining a flat annular surface about the outlet end of said passage, a plurality of peripherally spaced ports opening from said space about the discharge end 125 of said tube, means for supplying a mixture of fuel and air to said tube, and means for supplying supplemental fuel to said space. 130
5. A burner comprising, in combination, a burner tube having a straight longitudinal passage opening therethrough, the outlet end of said passage being flared outwardly on a relatively small radius, a sleeve fitting about said tube and defining an annular space therewith, the end of said sleeve defining a flat annular surface about the flared outlet end of said passage, a plurality of peripherally spaced ports opening from said space to said surface about the discharge end of said tube, an annular air space 135 opening about the discharge end of said tube, a mean for supplying a mixture of fuel and air under pressure to said tube, and means for supplying fuel to said first mentioned space. 140
6. A burner comprising, in combination, a tuyère, a burner tube smaller in diameter than 150

- 5 said tuyère and disposed in axial alignment therewith, said tube being formed with a central passage and an annular chamber about said passage having a plurality of outlet ports discharging about the outlet end of said passage into said tuyère, a concentric sleeve mounted in peripherally spaced relation on said tube and about said tuyère and formed with a plurality of peripherally spaced openings, a shutter rotatably mounted on said sleeve and formed with a plurality of peripherally spaced openings adjustable into various degrees of registration with said first mentioned openings, means for supplying a proportionate mixture of fuel and air to said tube and being adjustable to vary the volume of said mixture and to vary the proportion of fuel and air in said mixture, and means for supplying supplemental fuel to said chamber.
- 10 7. A burner comprising, in combination, a tuyère, a burner tube having a longitudinal passage opening therethrough, the exterior of said tube being recessed peripherally with a shoulder at the discharge tip, a sleeve fitting about said burner tube and defining a closed annular space therewith, a plurality of peripherally spaced ports formed in said shoulder and opening from said space to said tuyère, a casing connected to the inlet end of said tube, a nozzle in said casing and discharging into said tube, a valve controlled line for supplying fuel to said nozzle, means for admitting air to said casing, and a line connecting said first mentioned line to said space.
- 15 8. A burner comprising, in combination, a tuyère, a burner tube having a longitudinal passage opening therethrough and discharging to said tuyère, a chamber about said tube, a plurality of spaced ports formed in the tip of said tube and opening from said chamber to said tuyère, a suction chamber connected to the inlet end of said tube, a nozzle adapted to discharge into the inlet end of said tube, a line for supplying a fuel under a high pressure to said nozzle, means for supplying air to said suction chamber, and a line branching from said first mentioned line for supplying a small stream of supplemental fuel to said first mentioned chamber.
- 20 9. A gas burner comprising, in combination, an elongated burner tube having a discharge tip at one end, a casing connected to and in communication with the other end of said tube, said casing having an atmospheric air inlet opening, an adjustable shutter for controlling the effective area of said opening, a restricted injector nozzle mounted in said casing to discharge axially into said other end of said tube, means for discharging a restricted quantity of gas to said discharge tip
- 25 about the periphery thereof, a gas supply line connected to said nozzle, a control valve in said line, a line branching from said first mentioned line at the discharge side of said valve and connected to said means, and pressure reducing means in said last mentioned line.
- 30 10. A burner comprising, in combination, a burner tube having a passage of which the discharge end is flared convexly, the discharge tip of said tube being peripherally unconfined and defining a flat annular end surface merging with the outer peripheral margin of the flared portion of said passage, means for supplying fuel to the discharge tip of said tube at said surface, and means for supplying a stream of a fuel and air mixture at a relatively high velocity through said passage, said stream acting to induce a flow of supplemental air about the discharge tip of said tube and a flow of fuel from said first mentioned means into said stream.
- 35 11. A burner comprising, in combination, a body having an elongated discharge passage and a peripheral space, said body being formed with a plurality of peripherally spaced ports opening from said space about the outlet end of said passage, a casing on said body in communication with the inlet end of said passage, said casing having an air inlet, a shutter adjustably mounted on said casing for regulating the effective opening of said air inlet, a restricted nozzle in said casing for discharging axially into said passage, a high pressure fuel line connected to said nozzle, a regulating valve in said line, and a supplemental line branching from said fuel line and connected to said space.
- 40 12. A burner comprising, in combination, a body having an elongated discharge passage and a peripheral space, said body being formed with a plurality of peripherally spaced ports opening from said space about the outlet end of said passage, a casing on said body in communication with the inlet end of said passage, said casing having an air inlet, a shutter adjustably mounted on said casing for regulating the effective opening of said air inlet, a restricted nozzle in said casing for discharging axially into said passage, a high pressure fuel line connected to said nozzle, a regulating valve in said line, a supplemental line branching from said fuel line between said nozzle and said valve and connected to said space, and pressure reducing means in said branch line, said air inlet when fully open not permitting the admission of sufficient primary air to produce a combining air-fuel ratio in said passage.
